Application April 14, 1932, Serial No. 605,206

11 Claims. (Cl. 206—42)

This invention relates to containers or boxes adapted to hold commodities such as tablets or pills, the principal object of the invention being the production of a box of simple construction 5 having means permitting ready access to the contents of the box, without the necessity of removing or opening a cover member.

To the above ends the invention consists in the novel box and parts thereof hereinafter 10 more particularly described and then specified in the claims.

In the accompanying drawings showing a practical embodiment of the invention:

Fig. 1 is a perspective view of the box of the 15 invention.

Fig. 2 is a perspective view of the three parts of the box before they have been assembled together.

Fig. 3 is a section on the line 3—3 of Fig. 1. 20 Fig. 4 is a section on the line 4—4 of Fig. 1.

Fig. 5 is a plan view of a modification.

Fig. 6 is a horizontal section on the line 6—6 25 of Fig. 5.

Fig. 7 is a vertical cross-section on the line 7—7 of Fig. 5.

Fig. 8 is a perspective view of the three parts of the box of the invention of Fig. 5 before they have been assembled together.

Fig. 9 is a plan view of a further modification.

Fig. 10 is a horizontal section on the line 10—10 of Fig. 9.

Fig. 11 is a vertical cross-section on the line 11—11 of Fig. 9.

Fig. 12 is a perspective view of a further modi- 35 fication.

Fig. 13 is a section on the line 13—13 of Fig. 12.

Fig. 14 is a section on the line 14—14 of Fig. 40 12.

Fig. 15 is a perspective view of a further modi- 45 fication.

Fig. 16 is a perspective view of the three parts of the box shown in Fig. 15 before they have been assembled together.

Fig. 17 is a section on the line 17—17 of Fig. 15.

Referring in detail to the several figures of the drawings:

10 indicates the box body comprising a base 50 as shown provided with the usual upstanding flanges 11 while 12 indicates the box cover also comprising a base provided with the usual de- pending flanges 13 adapted to interfit over the flanges 11. The cover 12 is provided with a slot 55 14 and an annular opening 15 adjacent a corner thereof as well as with a downwardly projecting lug 16. The flanges 11 of the box body are pro- vided with inwardly extending lugs 17 positioned as illustrated.

60 A closure plate is indicated at 18. It is pro-

vided with downwardly extending flanges 19 5 slidably engaging the base or bottom of the box body as well as the opposed side walls thereof. It has an upwardly extending pin 20 constituting a finger piece and extending through the slot 14 and it is also provided with a depression 21 for receiving the lug 16 on the box cover, the two members constituting a detachable lock to hold the closure plate 18 in closed position to cover the opening 15 as shown in Fig. 1.

When the parts are assembled together the 10 cover is held to the box body by a very tight frictional engagement or it is otherwise clinched over said body it being understood and will be apparent that it is not necessary to remove said 15 cover to obtain access to the contents of the box. When access is desired, pressure is applied against the finger piece 20 whereupon the lug 16 will snap out of the depression 21 and the closure plate 18 may then be slid to open position 20 within the box to uncover the opening 15. When the cover plate is closed the lug 16 again automatically snaps within the depression 21 to detachably lock said closure plate in closed position. Assuming the contents of the box to be 25 pills or tablets, the lugs 17 have been provided to prevent the pill or tablet to be removed from lying in the corner of the box and to make it assume a position in alignment with the opening 30 15.

In the modification illustrated in Figs. 5 to 8 inclusive we provide the sides of the box body with shouldered portions 22 within which portions the flanges 19 of the closure plate ride. 35 Otherwise the operation is similar to that of the preferred form of the invention.

In the modification illustrated in Figs. 9 to 11 inclusive we provide a slot 23 somewhat wider than the slot 14 of the preferred form of the invention and having a finger piece 24 mounted on the closure plate for enclosing the opening 15, said finger piece being, by preference, of a shape and size simulating the tablets contained in the box. Said finger piece could be marked 45 with advertising matter if so desired.

In the modification illustrated in Figs. 12 to 14 inclusive the box body is provided with a slot 25 registering with a slot 26 in the box cover and the finger piece 27 for the closure member is 50 attached to one of its depending flanges 19 and rides in said slots.

In the modification illustrated in Figs. 15 to 17 inclusive the box cover is slotted as at 28 in one of its side members which registers with a 55 similar slot 29 in the box body. In this case we dispense with the opening 15 in the box cover and obtain access to the contents of the box through said slots. The closure member is provided with a finger piece 30 which rides in said slots as in 60

the case of the modification illustrated in Figs. 12 to 14 inclusive.

It will be understood also that in some cases we propose to reverse the parts shown in the preferred form of the invention and place the slot 14 and opening 15 in the body portion of the box instead of the cover portion in which case, of course, the position of the closure member 18 would be reversed and its flanges 19 would then ride on the underside of the cover member instead of on the body member. This construction would be used when it was desired to retain all the space on the top of the cover member for lithographing material.

15 The invention claimed is:

1. A box comprising a cover member and a body member interfitting with each other and provided with an opening in one of said members, a slideable closure member in said box, means for detachably holding said closure member in closed position and means for both depressing the slideable closure for releasing the holding means and for sliding said closure.

2. A box comprising a cover member and a body member interfitting with each other and provided with an opening in one of said members, a slideable closure member in said box, means for actuating said closure member to open or close said opening and inwardly pressed lugs at opposite sides of said opening adjacent thereto for preventing an article contained in the box from lying in the corner thereof.

3. A box comprising a cover member and a body member interfitting with each other and provided with an opening in one of said members adjacent a corner of the box, a slideable closure member in said box, means for actuating said closure member to open or close said opening, said box providing side walls meeting at the corner provided with said opening, and inwardly pressed lugs in said meeting side walls adjacent said opening for locating an article contained in the box at the opening and cause it to assume a position in alignment with said opening.

45 4. A box comprising a cover member and a body member interfitting with each other and provided with an opening in one of said members adjacent a corner of said box, a slideable closure member in said box, means for actuating said closure member to open or close said opening and inwardly pressed lugs in said box adjacent the corner in which said opening is located.

5. A box comprising a flanged cover member and a flanged body member interfitting with each other and provided with an opening in one of said members adjacent a corner of said box and with a slot in one of said members, a slideable closure member slideable against opposite flanges of one of said members, a pin extending from said closure member and through said slot and providing an actuator to cause said closure member to open or close said opening, cooperating means on said closure member and on one of said body or cover members to detachably hold said closure member in closed position and inwardly pressed lugs on one of said body or cover members in the corner of said box adjacent the aforesaid opening.

6. A box comprising a flanged cover member and a flanged body member interfitting with and tightly engaging each other substantially throughout the depth of said flanges with a flange of each member provided with a slot registering with a slot in the other member, a slide-

able closure member in said box and means extending laterally from said closure member and through said slots to move longitudinally thereof for opening and closing the same.

7. A box comprising a cover member and a body member interfitting with each other, one of said members being provided with an opening therein and one of said members being provided with a shouldered portion, a slideable closure member in said box, means for actuating said closure member to open or close said opening and a flanged guiding member on said closure member extending within said shouldered portion and adapted to ride therein and on the base of one of said members when said closure member is actuated.

8. A box comprising a flanged cover member and a flanged body member providing a top and bottom for said box and the flanges of said members interfitting with and tightly engaging each other, and one of said members having an opening and a slot, a slideable closure member in said box positioned at the inside of the inner interfitting flanges and member, said closure having flanges flatwise engaging the inner faces of said inner flanges and of substantially the same depth thereas, thereby confining said closure in slideable contact with the top and bottom and with opposite flanges inside the box and an actuating device extending from said closure member and through said slot for actuating said closure member to open or close said opening.

9. A box comprising a cover member and a body member interfitting with each other and provided with an opening in one of said members, each of said members comprising a base having flanges extending therefrom to form walls, a slideable closure member inside of the inner of said members and flanges thereof and comprising a plate having projecting flanges slidably engaging flatwise against the inner sides of a pair of the opposed flanges of the inner member and with longitudinal edges of the closure flanges slidably engaging the base of one of said members, and means for actuating said closure member to open or close said opening.

10. A box comprising a flanged cover member and a flanged body member each provided with slots in one of their flanges registering with each other and one of said members being provided with an opening, a slideable closure member in said box having flanges slidably engaging opposed flanges on one of said members to open or close said opening and means extending through said slots and connected to a flange on said closure member for actuating said closure member to open or close said opening with the closure member at all times entirely within the box and with the actuating means therefor moving longitudinally of said slots.

11. A box comprising a flanged cover member and a flanged body member interfitting with and lockingly engaging each other with a flange of each member provided with a registering slot, a slideable closure member in said box having flanges slidably engaging opposed flanges on one of said members to open or close said openings and means extending laterally from said closure member and through said slots to move longitudinally thereof for opening and closing the same.
